(57) CLAIM

The ornamental design for electrical connector assembly, as shown and described.

DESCRIPTION

FIG. 1 is a perspective view of electrical connector assembly showing my new design;

FIG. 2 is a side view thereof;

FIG. 3 is a top view thereof;

FIG. 4 is a bottom view thereof;

FIG. 5 is an alternate side view thereof;

FIG. 6 is an end view thereof; and,

FIG. 7 is an opposite end view thereof.

The broken line showing of the environment is for illustrative purpose only and forms no part of the claimed design.
